UNITED STATES PATENT OFFICE.

CHARLES H. MEIGS, OF PHILADELPHIA, PENNSYLVANIA, ASSIGNOR, BY MESNE ASSIGNMENTS, TO FOAMITE FIREFOAM COMPANY, OF NEW YORK, N. Y., A CORPORATION OF DELAWARE.

FIRE-EXTINGUISHING APPARATUS.

1,296,993.

Specification of Letters Patent.

Patented Mar. 11, 1919.

Application filed January 11, 1918. Serial No. 211,350.

To all whom it may concern:

Be it known that I, CHARLES H. MEIGS, a citizen of the United States, residing at Philadelphia, in the county of Philadelphia and State of Pennsylvania, have invented new and useful Improvements in Fire-Extinguishing Apparatus, of which the following is a specification.

This invention relates to improvements in fire-extinguishing apparatus, pertaining more particularly to apparatus of the portable type, sometimes termed "hand extinguishers."

Extinguishers of this type, when employed in the production of an extinguishing medium produced under foam-extinguishing principles, require an acid container or receptacle of a considerably greater content than the usual acid receptacle, thus providing a problem which differs from the problems of the usual acid and soda type of extinguisher, in that the largely increased size receptacle presents several factors which must be considered. For instance, the increased length and increased amount of acid solution provides a weight factor of importance both with respect to the bottom of the extinguisher and in connection with movement of the acid receptacle by shaking or otherwise moving the extinguisher.

This change in size and the use of an acid solution instead of the usual concentrated form of acid brings about another difficulty in connection with the use of the ordinary type of extinguisher in the tendency of the acid content to produce a crystallizing effect on the walls of the receptacle not covered by the solution itself. It has been found that where the extinguisher has been shaken to a material extent, thus carrying the solution to the stopper or stopple seat, the deposits may be crystallized to such an extent as to tend to bind the stopple to its seat, thus oftentimes requiring considerable pressure to release the stopple. Where the apparatus is designed for release of the stopple under gravity conditions, this binding may materially affect the operation of the extinguisher.

The present invention is designed more particularly to meet these problems by employing an inner container which is practically clamped in position so as to restrict the movements of the inner container, and at

the same time more or less eliminate the sticking of the stopple to its seat under the crystallization action, the result being the production of an extinguisher in which the inner container is removable bodily from the extinguisher in a simple manner, is practically clamped in position when within the extinguisher, and which provides assurance of the movements of the stopple automatically from its seat when the extinguisher is inverted. In addition, the structure is one which permits of the use of extinguishers of prior types with but small changes to prepare the outer casing or receptacle for the reception of the inner container, thus permitting utilization of the large number of extinguisher structures heretofore marketed and reducing the cost of installation, as well as providing a construction which is simple and efficient in operation, durable in construction, and which can be produced as a complete structure at a comparatively low cost.

To these and other ends, therefore, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views:

Fig. 1 is a sectional view taken vertically through a preferred form of my apparatus.

Fig. 2 is an enlarged detail view partly in section and partly in elevation of the upper end structure of the apparatus, the line of section being shifted from that shown in Fig. 1.

Fig. 3 is a fragmentary top plan view of the apparatus with the cap removed.

Fig. 4 is a detail of the receptacle-supporting element.

Since operations under the foam-extinguishing process generally have the amount of acid solution more closely approximating that of the soda solution than in the ordinary type of operations, the container for the acid solution is of materially increased capacity, a preferred arrangement having a length sufficient to reach to the bottom

of the outer receptacle, the inner receptacle or container being of a size to permit of ready insertion and removal through the usual mouth or neck of the outer casing or 5 receptacle, thus providing a capacity sufficient to produce the desired relative proportions of soda and acid solutions, it being understood that the acid solution is placed within the inner container.

10 This length of container, when the latter is provided with its charge, is more or less weighty and therefore there is a liability to shift the inner receptacle or container during movements of the extinguisher, as when 15 being carried about. This shifting may tend to damage the bottom of the extinguisher, especially where the container is supported by the bottom. In this latter case, there is also liability of damage by reason 20 of the weight, where the extinguisher forms a part of the equipment of a fire department and is carried by a hose carriage, in which case the jars, etc., incident to the travel of the carriage, may provide for a 25 damaging action on the extinguisher bottom.

To avoid these difficulties it is desirable not only that the opposite ends of the container be supported in such manner as to 30 limit lateral shifting movements to the minimum, but, in addition, an additional safeguard is had by providing the support for the container at the normally upper end of the extinguisher, thus causing the 35 container to have a more or less suspended effect, although it is preferred that the lower end of the container be so supported as to prevent this shifting action.

The present invention is designed to provide 40 this action, and in the drawings I have shown one way in which these results can be obtained, 10 designating the casing, 11 the bottom, 12 the top or neck to which the cap 13 is threaded, and 14 the discharge element for the extinguishing medium, these parts being of the general type heretofore employed, with the possible exception of the particular configuration of the bottom 11, the latter preferably being varied somewhat 45 from the similar part of the usual soda and acid extinguisher structure. This change in the bottom practically provides for the formation of a central depression 11^a in the bottom, within which the lower 50 end of the inner container extends, a loose fit being provided to permit of the ready insertion and removal of the container and yet substantially maintain the lower end of the latter against shifting action.

60 The inner removable receptacle or container is indicated at 15, the receptacle having a gravity closure or stopple 16 at its open end. 17 indicates a cage structure for the stopple, this structure being formed by 65 a plurality of vertically extending straps

17^a—four being shown in the drawings—secured to the receptacle at equal distances, and projecting above the top of the receptacle. The straps are preferably formed with ribs 17^b, although these are not absolutely essential, these ribs projecting outwardly or inwardly as may be found desirable. As shown, the straps are shaped to provide an increased space above the top of the receptacle to permit of ready shifting of 75 the stopple away from its seat. The upper ends of straps 17^a are secured to a ring or annulus 18, as by rivets 18^a. It is to be understood, of course, that the cage structure thus provided has over-all dimensions 80 such as will permit of its passage into the filling opening or mouth of the extinguisher.

19 designates a supporting member or seat which is secured, by suitable means, to the 85 interior of neck 12. Member 19, as shown more particularly in Fig. 4, is in the form of an annular ring having inturned segmental flanges 19^a, these flanges being spaced apart to provide openings through 90 which straps 17^a extend, flanges 19^a forming a seat for the intermediate portions of annulus 18. The diameter of receptacle or container 15 is such as to freely pass the flanges 19^a, and the strap formation is such 95 that where, during insertion of the container, the straps do not coincide with the recesses formed in the seat flange of member 19, the container will not pass to its seat by reason of contact of the offset portions 17^c of the straps with the segments 19^a, thus leaving the cage exposed as an indication of improper seating. The receptacle can then be readily turned until the straps aline with the recesses of member 19, 105 permitting the container to pass to its seated position, the straps preventing shifting of the container on its axis, while the support for annulus 18 provided by flanges 19^a will support the container at its upper end, so 110 that even should the lower end be in contact with the bottom, there is practically no liability of the latter being damaged owing to the fact that the particular mounting is such as to produce a more or less suspension 115 effect to the container.

As heretofore pointed out, there is, in practice, an inherent action which tends to affect the automatic action of the stopple or closure which is desired when the extinguisher is turned end for end in use. This action is a more or less crystallization of the metallic salts contained in the acid solution, shaking of the container, etc., causing the solution to pass into contact with the stopple 125 and bringing about a condition which will permit crystallization action to take place. While slight crystallization might not normally materially affect the arrangement, the inherent action is such that there is a 130

tendency to increase this crystallization action, there being possibly a more or less capillary action present which causes the deposits to build up, thus uniting the 5 stopple and the upper end of the container by this crystallization deposit. Since the stopple is of the gravity type and is shiftable under shaking action, it will be readily understood that this crystallization effect 10 can take place even between the upper edge of the container and the bottom of the groove within which the latter seats, thus increasing the crystallization area and rendering it more difficult to unseat the 15 stopple when it is desired to use the extinguisher. Even though this crystallization action may not be provided at all points of the stopple, the effect is more or less objectionable by reason of the fact that, under 20 such conditions, there is a tendency for the stopple to cant in attempting to leave its seat, thus affecting the desired action through inability to provide for complete discharge of the contents of the container in 25 the manner desired.

This particular difficulty is practically eliminated by the particular manner of forming the mouth of the container, in connection with the particular form of stopple 30 employed. This is provided by securing an annulus 25 internal of the open end or mouth of container 15, this annulus being so formed as to provide a shoulder 25^a at the lower end of the annulus. This shoulder 35 is shown as extending at right angles to the axis of the annulus, but it will be understood that if desired, this may be varied. As shown, annulus 25 projects above the upper end of container 15, the projecting 40 portion having its outer periphery tapered inwardly toward the top of the annulus, thus causing the upper edge of the annulus to be more or less of the character of a knife edge, thereby providing an exceedingly 45 narrow area of contact between the annulus and the bottom of the groove of the stopple, the knife edge forming a stopple seat extending on a plane substantially transverse to the axis of the receptacle.

50 The bottom of groove 16^a of stopple 16, is of materially greater width than the edge of annulus 25, and the sides of the groove are flared outwardly so as to provide for easy positioning action of the stopple on such edge.

55 As will be understood, the presence of shoulder 25^a in the path of the contents during splashing action, tends to decrease the liability of the salts reaching the knife edge, 60 and, more particularly, to decrease capillary action in building up any deposits which might be formed. In addition, the only point of contact between stopple and container is provided along the knife-like edge 65 of the container, so that there is a minimum

surface contact which can provide the uniting action. And since the stopple groove and knife edge are so arranged as to provide for a loose fit, therebetween, it will be readily understood that a shaking action which 70 would tend to bring the contents to such point, would also tend to shift the stopple on its seat and thus break down any uniting action which had taken place previously.

75 By the use of means for materially limiting if not entirely eliminating the effects of crystallization, no provision need be made for producing a special jarring action in an attempt to dislodge a stopple which has "stuck" by reason of the crystallization action. And since no special action of this kind is necessary, it is possible to practically maintain the container in its proper position by the use of a gasket 13^a interposed between the cap 13 and the upper end of the 80 cage, thus practically clamping the structure in position to decrease the possibility of shifting of the container relative to the casing.

85 In smaller sizes, this particular manner of supporting the upper end of the container and the clamped condition may provide sufficient resistance to shifting action as to permit dispensing of the use of depression 11^a, the container practically reaching to 90 the ordinary bottom and being maintained in position by reason of the support at the upper end and the clamping action provided. As will be understood, the support at the upper end enables the weight effect to 95 be placed upon a stronger and more substantial portion of the container than upon the normal bottom which is generally of copper and more or less easily damaged.

100 It will therefore be understood that while I prefer to employ the depression 11^a or its operative equivalent, this is not absolutely essential and I may omit it without departing from the spirit of the invention.

105 While I have herein shown preferred ways in which the invention may be carried into effect, it will be readily understood that changes and modifications therein may be found desirable or essential in meeting the various exigencies of use, and I desire to be 110 understood as reserving the right to make any and all such changes or modifications as may be found necessary or desirable, in so far as the same may fall within the spirit and scope of the invention as expressed in 115 the accompanying claims when broadly construed.

120 Having thus described my invention, what I claim as new is:

125 1. In portable fire extinguishers adapted for the production and discharge of foam-extinguishing compounds, the combination with a casing having a neck and a bottom, a discharging element for the extinguishing medium, and a cap, of a removable re-

- ceptacle therein having a closure and a cage for the closure, said cage including a plurality of straps, and a seat for the cage carried by the casing neck, said seat acting to support the receptacle in position and coöperating with the straps to prevent rotative movement of the receptacle on its axis, said closure being normally free to shift to permit discharge of receptacle contents.
- 10 2. In portable fire extinguishers adapted for the production and discharge of foam-extinguishing compounds, the combination with a casing having a neck and a bottom, a discharging element for the extinguishing medium, and a cap, of a removable receptacle therein having a closure and a cage for the closure, said cage including a plurality of straps and an annulus connecting the outer ends of the straps, and a
- 15 seat for the cage carried by the casing neck, said cap and seat coöperating to clamp the said annulus to support the receptacle in position, said seat and straps coöperating to prevent rotative movement of the receptacle on its axis, said closure being normally free to shift to permit discharge of receptacle contents.
3. In fire extinguishers, a casing having a bottom, a removable receptacle therein, said casing and receptacle having openings at corresponding ends, a member carried by the casing within its opening, said member being provided with spaced recesses, a cage structure carried by the receptacle and
- 20 projecting beyond its opening and adapted to coöperate with the recesses in said member to prevent rotation of the receptacle, and a gravity closure freely movable within the cage.
- 25 4. In fire extinguishers, a casing, a removable receptacle therein, said casing and receptacle having openings at corresponding ends, a seat carried by the casing within its opening, a cage structure carried by the receptacle beyond its opening and including a plurality of straps and an annulus connecting the outer ends of the straps, said cage and seat being complementally formed to removably support the
- 30 receptacle on the seat and to cause seat and strap coöperation to prevent rotative movements of the receptacle on its axis, and a gravity closure freely movable within the cage.
- 35 5. In fire extinguishers, a casing, a removable receptacle therein, said casing and receptacle having openings at corresponding ends, a seat carried by the casing within its openings, said seat having spaced segmental flanges extending inwardly, a cage structure carried by the receptacle beyond its opening, said cage structure including a plurality of straps and an annulus connecting the outer ends of the straps, said
- 40 straps being positioned to be received within and substantially filling the spaces between the segmental flanges of the seat, said annulus and the flanges coöperating to support the receptacle in position, and a gravity closure freely movable within the cage.
- 45 6. In fire extinguishers, a casing, a receptacle therein, said casing and receptacle having openings at corresponding ends, a cage structure carried by said receptacle and projecting beyond its opening, said structure including straps and an annulus connecting the free ends of the straps, said straps having shoulders, a gravity closure freely movable in the cage, and a receptacle-supporting member carried by the casing within its opening, said member having spaced inwardly-extending segmental flanges, said flanges forming seats for said strap shoulders when the straps are out of alinement with the spaces between flanges and a seat for the annulus when the straps and spaces are alined.
- 50 7. In fire extinguishers having an inner open ended receptacle for the acid solution and a closure for the receptacle, means carried by the receptacle for restricting the effects of crystallization action of the contained solution on the movement of the closure, said means including a closure seat extending on a plane transverse to the axis of the receptacle, and an annular shoulder internal of the receptacle and spaced from said seat.
- 55 8. In fire extinguishers having an inner receptacle for the acid solution, said receptacle having a mouth, of an annular member carried interiorly of the receptacle at its mouth and adapted to form a shoulder therein, said member projecting beyond the mouth with the projecting portion formed to produce an annular seat for a closure, said seat being of limited contact area, whereby the effects of crystallization action of receptacle contents on the movement of the closure is restricted.
- 60 9. In fire extinguishers having an inner receptacle for the acid solution, said receptacle having a mouth, of an annular member carried interiorly of the receptacle at its mouth and adapted to form a shoulder therein, said member projecting beyond the mouth with the projecting portion formed to produce an annular knife-like seat for the closure, whereby the effects of crystallization action of receptacle contents on the movement of the closure is restricted.
- 65 10. In fire extinguishers having an inner receptacle for the acid solution, said receptacle having a mouth, of an annular member carried interiorly of the receptacle at its mouth and adapted to form a shoulder therein, said member projecting beyond the mouth and forming a seat for a closure, and a closure for the receptacle, said closure hav-

5 ing an annular groove to receive the seat face, said groove having a bottom of greater width than the width of the seat face, whereby the effects of crystallization action of receptacle contents on the movement of the closure is restricted.

11. In fire extinguishers having an inner receptacle for the acid solution, said receptacle having a mouth, of an annular member 10 carried interiorly of the receptacle at its mouth and adapted to form a shoulder therein, said member projecting beyond the mouth and forming a seat for a closure, and a gravity closure having an annular groove to re-

ceive the seat face, said groove having a 15 bottom of greater width than the width of the seat face with the sides of the groove flared outwardly, whereby the effects of crystallization action of receptacle contents on the movement of the closure is restricted. 20

In testimony whereof I have hereunto set my hand in presence of two subscribing witnesses.
